[57] CLAIM

The ornamental design for a post for cart, as shown and described.

DESCRIPTION

FIG. 1 is a top front perspective view of a post for cart showing our new design;

FIG. 2 is a top plan view thereof, the bottom plan view being a mirror image;

FIG. 3 is a right side lateral view thereof, the left side lateral view being a mirror image;

FIG. 4 is a front elevational view thereof; and,

FIG. 5 is a top front perspective view of the post for cart illustrating its configuration within a cart. The broken line showing of a cart is for illustrative purposes only and forms no part of the claimed design.

1 Claim, 3 Drawing Sheets
